TRACK SANDER FOR LOCOMOTIVES

Guilford S. Turner, Chicago, Ill., assignor to Morris B. Brewster Co., Chicago, Ill., a corporation of Illinois

Application November 5, 1942, Serial No. 464,573

2 Claims. (Cl. 291—16)

The invention relates to track sanders for locomotives.

It is now common practice to provide sand-traps provided with nozzles for delivering air under pressure to discharge sand from the trap and through a pipe for delivering sand to the rails and also with ducts for short clean-out blasts directly into the delivery pipes at the beginning and end of each sanding operation and to control the air from the nozzle and for the clean-out blast from a single manually controlled operator's valve. These operator's valves have been constructed to initially control the delivery of air to the clean-out ducts or nozzles in the traps and in succession to the sand-discharge nozzles during a single continuous movement of the lever on the operator's valve. In practice it has been found that the turbulence produced in the sand-traps by the clean-out air prior to the delivery of air to the sand delivery nozzles frequently causes the sand to work back into the air line from the trap to the operating valve. Sand so forced back into the operating valve when the latter is of the disk type is likely to reach the contacting surfaces of the disk valve and its seat and produce cutting of said surfaces or to render the valve inefficient.

The primary object of the present invention is to provide track sanding equipment of this type which comprises an operator's valve of the disk type which is provided with ports for successively controlling the delivery of compressed air to the clean-out and sand delivery nozzles and which is provided with simple and efficient means in the operator's valve for causing a sufficient but restricted flow of air to the sand delivery nozzle while, and preferably before, air is delivered to the clean out duct to produce sufficient counter pressure on the trap to prevent any sand from being forced back from the trap and through the pipe for delivering air to the sand delivery nozzle into the operating valve.

Other objects of the invention will appear from the detailed description.

In the drawing:

Fig. 1 is a side elevation of sanding equipment embodying the invention.

Fig. 2 is a vertical transverse section through the operator's control valve.

Fig. 3 is a section taken on line 3—3 of Fig. 2.

Fig. 4 is a face view of the section of the valve casing in which the valve disk is seated and the outlet connections leading from the valve casing to the pipes for delivering compressed air to the

sand delivery nozzles and the clean-out ducts of a pair of sand-traps.

Fig. 5 is a view of the face of the valve disk which fits against the valve seat in the casing, rotated into position to commence the delivery of air to the clean-out ducts, the outlet ports in the casing being shown on dotted lines.

Fig. 6 is a section taken on line 6—6 of Fig. 3.

The invention is exemplified in sanding equipment which comprises a sand-trap 8 which is provided with an inlet leg for receiving sand from a pipe 9 to which sand flows from a sand box in the dome of the locomotive, as well understood in the art. The trap is provided with an outlet 10 for sand to which is connected a pipe 11 for conducting sand to a track rail. A nozzle 12 in the sand-trap is adapted to deliver air under pressure into the trap conduit to discharge the sand through the discharge duct 10 into pipe 11. An air pipe 13 from the operator's valve is connected to the casing of the trap to deliver air to the nozzle 12. A duct or nozzle 14 is formed in the casing 8 to direct a clean-out blast into the pipe 11 and a pipe 15 conducts air from the operator's valve to said duct 14.

The operator's valve illustrated is adapted to control the supply of compressed air to the sand delivery nozzles 12 and the clean-out ducts 14 of a pair of traps, only one of which is shown. This valve comprises a casing or body composed of an inlet section 18 and an outlet section 19 which are fixedly secured together by bolts 20. The inlet section 18 is provided with a chamber 21 to which an inlet pipe 22 is connected for compressed air from a supply tank, as well understood in the art. The outlet section 19 of the casing has connected thereto a pair of pipes 13 for conducting air to the sand delivery nozzles 12 of a pair of traps 8, and a pair of pipes 15 for conducting air from the operator's valve to the clean-out ducts 14 of a pair of sand-traps 8. The inner face 23 of the casing section 19 is ground to form a flat seat for one face of the valve disk 25 which controls the flow of compressed air from the inlet section 18 to the outlet section 19 of the valve casing. A spring 26 is interposed between casing section 18 and a stud 27 which engages the disk 25 to hold the disk against the seat 23. A pair of ports 28 are formed in the outlet section 19 of the casing which extend radially in and lead from the face 23 which forms the seat for the valve disk 25 to the pipes 13 which conduct compressed air to the sand delivery nozzles 12 respectively. A pair of ports 29 in the outlet section 19 extend radially in and

from the valve seat 23 and to the pipes 15 which conduct air to the clean out nozzles 14 of a pair of sandtraps respectively. The valve disk 25 is provided with a pair of radially extending outwardly divergent through-ports 30 which are adapted, when the disk is rotated approximately 45° from its normal position, to successively register with the ports 28 in the outlet section 19 of the valve casing for delivering air to the sand delivery nozzles 12, and with a pair of radially extending outwardly divergent through ports 31 which are adapted to register with the ports 29 in the outlet section of the casing when the disk has been rotated approximately 22½° from its normal position. A stem 32 is journaled in the outlet section 19 of the casing and provided with a head 33 which fits in a socket in the disk 25 and is adapted to rotate said disk. A lever 34 is fixedly secured to the outer end of stem 32 and the casing section 19 is provided with stops 35 from limiting the throw of the lever to substantially 45°. A spring pressed detent or roller 34a is slidably mounted in the handle lever 34 and is adapted to enter notches in the casing section 19 for yieldingly holding the lever 34 and disk 25 in normal and sanding positions. When the lever 34 is in its normal position all of the ports in the valve seat 23 will be closed by disk 25. When the lever 34 is shifted to its sanding position the ports 31 in the disk 25 will first uncover the ports 29 in the outlet section 19 of the casing and compressed air will pass through ports 29 and pipes 15 to the clean-out ducts 14 of the sand-traps and further movement of the hand lever will rotate the disk 25 to cover the ports 31 and bring the ports 30 in disk 25 into registry with the ports 28 in casing section 19 and cause compressed air to flow through pipes 13 to the sander nozzles 12 in the traps.

The valve disk 25 is provided with a pair of small holes or through ports 36 which communicate with small arcuate grooves 37 formed in the face of the disk 25 which engages the seat 23. The grooves 37 extend arcuately in the face of the disk 25 a sufficient distance so that they will lap the ports 28 preferably slightly before or as soon as the ports 31 in disk 25 admit air to the ports 29 through which air flows to the clean-out nozzles and to continue the restricted stream of air through ports 36 and grooves 37 to the ports 28 through which air flows to the sand delivery nozzles until after ports 31 in the disk 25 have passed and closed ports 29 and discontinued the supply of air to the clean-out ducts. As a result, during each full stroke of the lever 34 and its corresponding rotation of disk 25 a restricted stream of air will flow through ports 36 and grooves 37 to the sand delivery nozzles prior to, during, and shortly after the clean-out blasts which are controlled by the ports 31 in the disk 25. After said stream is cut off the ports 30 will register with ports 28 and supply air to the nozzles as long as the handle 34 is left in its fully shifted position.

The operation of the equipment will be as follows: During each full stroke of the lever 34, ports 31 in disk 25 will register with and pass over the ports 29 to deliver clean-out blasts to the nozzles 14; ports 29 will be closed and ports 30 in disk 25 will pass into registry with ports 28 in the outlet section 19 to deliver air to the sand delivery nozzles 12. Before air begins to flow through

ports 31 to ports 29, during the flow of air through ports 31 and 29, and if desired slightly after said ports 29 have been closed, by the continued movement of the disk and before the air flows through ports 30 and 28 to the sand delivery nozzles a restricted and sufficient flow of air will flow through holes 36 and grooves 37 from the chamber 21 to the ports 28 to deliver a restricted and sufficient flow of air to the sand-delivery nozzles to counteract the air from the clean-out ducts and thus prevent the sand in the traps from being forced backwardly through the pipes 13 into the valve section 19 and against the working face of the disk 25.

The invention exemplifies simple and efficient means for controlling, during a full stroke of an operator's valve, the successive delivery of compressed air to the clean-out nozzles and the sand delivery nozzles, and for producing a small but sufficient flow of compressed air to the sand delivery nozzles to oppose and prevent the clean-out blasts from forcing air through the sander nozzles to the operator's valve. This means is simple in construction and can be easily applied to operator's valves of the disk type which are now in use.

The invention is not to be understood as restricted to the details herein set forth since these may be modified within the scope of the appended claims without departing from the spirit and scope of the invention.

Having thus described the invention, what I claim as new and desire to secure by Letters Patent is:

1. An operator's valve for manually controlling the delivery of compressed air to the sand-discharge nozzle and a clean-out duct of a sand trap comprising a casing provided with a chamber supplied with compressed air, a face forming a seat, an outlet port leading from said face for supplying air to the sand-discharge nozzle and an outlet port leading from said face for supplying a blast of air to the clean-out duct, a manually rotatable valve disk fitting said seat and provided with separate through-ports arranged to register in rotative succession with the outlet port to the nozzle and the outlet port to the clean-out duct, and means in the disk for delivering a restricted flow of air to the outlet port to the sand-discharge nozzle during the delivery of air to the clean-out duct and before the disk is rotated into position for delivering the blast of air to the nozzle.

2. An operator's valve for manually controlling the delivery of compressed air to the sand-discharge nozzle and a clean-out duct of a sand trap comprising a casing provided with a chamber supplied with compressed air, a face forming a seat, an outlet port leading from said face for supplying air to the sand-discharge nozzle and an outlet port leading from said face for supplying a blast of air to the clean-out duct, and a manually rotatable valve disk fitting said seat, provided with through-ports arranged to register in rotative succession with the outlet ports to the nozzle and to the clean-out duct, and with a restricted port through and a channel in the face on the seat for delivering a restricted flow of air to the outlet port to the sand-discharge nozzle during the delivery of air to the clean-out duct and before the disk is rotated into position for delivering the blast of air to the nozzle.
